UNITED STATES PATENT OFFICE.

JOSEPH B. STANTON, OF ST. LOUIS, MISSOURI, ASSIGNOR TO W. N. MATTHEWS AND BROTHER, INC., OF ST. LOUIS, MISSOURI, A CORPORATION OF NEW MEXICO.

PUMP-VALVE.

1,355,285.

Specification of Letters Patent. Patented Oct. 12, 1920.

Application filed February 20, 1919. Serial No. 278,124.

To all whom it may concern:

Be it known that I, JOSEPH B. STANTON, a citizen of the United States, residing at St. Louis, Missouri, have invented a certain 5 new and useful Improvement in Pump-Valves, of which the following is a full, clear, and exact description, such as will enable others skilled in the art to which it appertains to make and use the same, reference being had to the accompanying drawings, forming part of this specification, in which—

Figure 1 is a vertical sectional view through a pump showing my improved 15 valve in position thereon.

Fig. 2 is a detail view of one of the valves.

Fig. 3 is a detail view of one of the valve 20 seats.

Fig. 4 is a detail view of a modified form 25 of valve.

Fig. 5 is a detail view of a valve seat for the form of valve shown in Fig. 4.

My invention relates to a new and useful 30 improvement in pump valves designed particularly for the type of pump shown and described in an application filed by George McD. Johns, Serial No. 272,944. The object of my present invention is to provide a removable valve seat which, being detachable, may be ground, together with the valve, without the necessity of handling the heavy 35 ported casting on which the valve seat is arranged and in this manner avoid warping of said valve seat due to pressing or screwing into said casting as in present practice is avoided.

In the drawings, 1 indicates the base of the pump having an inlet port 2 and an 40 outlet port 3. 4 indicates a casting suitably ported to communicate with the inlet and outlet ports, said casting providing a mount for the cylinder 5 in which operates a plunger 6. I have not shown the means for reciprocating this plunger, as the same forms 45 no part of my present invention.

The casting 4, before referred to, has a top wall 4^a through which open ports in said casting, as shown, and on each end of 50 casting 4 and on opposite sides of the cylinder 5 are arranged valve seats 7 provided with ports 8 communicating with the ports in casting 4. The valve seat 7 has a raised

boss 9 in which spider arms are arranged for supporting a guiding stud 10, on which 55 guiding stud is a rubber valve 11 held to its seat by means of a spring 12. 13 indicates a valve cap having a centering teat 14 for spring 12, said cap engaging the marginal flanges of the valve seat 7, as shown. 15 60 indicates a clamping member having laterally extending arms 15^a through which extend bolts 16, said bolts passing down through the base casting 1. By tightening the nuts on the bolts 16, the valve cap, valve 65 seat and ported casting 4 are clamped to the base casting 1. The engaging surfaces of these parts are preferably machine finished, and, if desired, leather gaskets or packing strips or washers may be employed between 70 the engaging surfaces.

Where hot liquids or chemicals are pumped which may disintegrate or affect the rubber valves 11, I can employ metal valves 17, such as shown in Fig. 4, which 75 metal valves coöperate with valve seats 18, as shown in Fig. 5. Where these metal valves are employed, the spring may or may not be used, as desired. The metal valve 17 is provided with an inner stud 17^a on its 80 top which serves to arrest its upward movement by coöoperating with teat 14 of the valve cap.

By making the valve seat separate and detachable, different metal can be employed 85 in its construction than that used in the base, the ported casting 4 and the valve cap, which are preferably made of cast iron. The valve seat may be made of brass or any other suitable material, and where liquids 90 such as water are to be pumped, which will not seriously affect rubber, rubber valves 11 may be used, or metal valves such as valve 17 may be employed where other liquids are to be pumped. The detachability of the 95 valve seat and the accessibility of the valve enables both the seat and the valve to be ground or refinished without necessitating the handling of the ported casting 4 and without danger of possibly warping or in- 100 juring the valve seat by its being refitted to the ported casting. Furthermore, the valve seats and valves can be readily renewed at little expense, without renewing other parts of the pump or replacing of the 105 casting thereof.

What I claim is:

A pump comprising a base casting, a ported casting, a cylinder arranged centrally thereof, valve seats on each end of 5 said ported casting, valves coöperating with said seats, valve caps, and clamping devices coöperating with each of said valve caps for

securing the same, the valve seats and opposite ends of the ported casting to the base casting.

10

In testimony whereof I hereunto affix my signature, this 18th day of February, 1919.

JOSEPH B. STANTON.
